F. G. SPENCER

CABLE CLAMP

Filed May 14, 1925

FIG. 1.

FIG. 2.

FIG. 3.

Inventor

Furman G. Spencer.

By Brockett, Hyde & Milburn
Attorneys

UNITED STATES PATENT OFFICE.

FURMAN G. SPENCER, OF LAKEWOOD, OHIO, ASSIGNOR TO THE UPSON WALTON COMPANY, OF CLEVELAND, OHIO, A CORPORATION OF OHIO.

CABLE CLAMP.

Application filed May 14, 1925. Serial No. 30,183.

This invention relates to cable clamps and has for its object the provision of an improved clamp which is of simple and inexpensive construction and extremely efficient 5 in its clamping action.

Further objects of the invention are in part obvious and in part will appear more in detail hereinafter.

In the drawing, Fig. 1 is an end elevation 10 of a cable clamp embodying my invention, part thereof being broken away; Fig. 2 is a side elevation with a part broken away; and Fig. 3 is a cross sectional view on the line 3—3, Fig. 2, the cable being shown in elevation.

Referring to the drawing, the present improved cable clamp includes a metal clamping jaw member comprising a substantially flat base portion 1 provided with two spaced 20 pairs of upwardly extending arms 2. The arms of each pair are suitably spaced apart to provide therebetween an opening or passageway 3 for the superposed or overlapping cable portions 4, which are clamped together 25 between the arms of the jaw member by a U-shaped bolt member 5. Said bolt member straddles said cable portions with its end portions extending through openings 6 in the clamping jaw member between the two 30 pairs of arms 2 thereof, as clearly shown in Figs. 1 and 3. The end portions of said bolt member extend below the clamping jaw member and are threaded as at 7, to receive the lock nuts 8, which, when tightened on 35 said threaded bolt portions, firmly clamp the two cable portions together between the bolt member and the clamping jaw member.

In order to increase the effective clamping

or binding action of the present clamp the four upwardly extending arms 2 are provided with downwardly and inwardly inclined inner faces 9 so that the opening 3 between each pair of arms is of substantially V-shape, with the result that when the lock nuts 8 are tightened upon the bolt member 5, the lower cable portion is firmly wedged and clamped 40 between each pair of arms, as clearly indicated in Fig. 1. To further increase the clamping or binding action of the present clamp, the inner faces 9 of each upwardly 45 extending arm 2 is convexly curved in a transverse direction, as clearly indicated in Fig. 3, so that the area of engagement of the lower cable portion with the inner face of each arm 2 is reduced to substantially a line, 50 as clearly indicated in Fig. 3.

The cable portions are, therefore, firmly and securely clamped or held together without liability of accidental loosening or disengagement thereof.

What I claim is:—

A cable clamp, comprising a clamping jaw member, and a U-shaped bolt member extending through openings therein and adapted to be secured thereto with the cable portions clamped therebetween, said clamping jaw member being provided on each side of said bolt openings with a pair of upwardly extending arms between each pair of which the cable portions extend, the inner face of each of said arms being inclined downwardly and inwardly and being convexly curved in transverse direction.

In testimony whereof I hereby affix my signature.

FURMAN G. SPENCER.
